UNITED STATES PATENT OFFICE.

THOMAS DUNBAR AND ETHAN I. DODDS, OF PULLMAN, ILLINOIS,
ASSIGNORS TO THE PULLMAN COMPANY, OF CHICAGO, ILLINOIS,
A CORPORATION OF ILLINOIS.

RAILWAY-CAR SILL.

No 825,042.

Specification of Letters Patent.

Patented July 3, 1906.

Application filed October 30, 1905. Serial No. 285,157.

To all whom it may concern:

Be it known that we, THOMAS DUNBAR and ETHAN I. DODDS, citizens of the United States, residing at Pullman, in the county of Cook and State of Illinois, have invented certain new and useful Improvements in Railway-Car Sills, of which the following is a specification.

The purpose of our invention is the provision of a metallic side or center sill for railway-cars which shall combine light weight, strength, and ease of repair. To carry out this object and embody the invention in practical form for each sill, we use two end members deeper at their inner than at their outer ends and join these inner ends at their upper parts by any standard form of bar and at their lower parts by a tension-rod comprising two pieces united by a turnbuckle. In this manner a bellied sill is manufactured which attains the object specified.

In the accompanying drawings is illustrated the preferred mechanical embodiment of our invention.

Figure 1 is a side elevation of one-half of the sill, and Fig. 2 is a vertical cross-section on line 2-2 of Fig. 1.

The sill comprises two end beams 10, of which only one is shown in the drawings. Each of these has a top integral inwardly-turned flange 11 and a similar bottom flange 12, the inner end portion 10^a of each beam being deeper than its outer end portion 10^b, as shown. A channel-bar 13 with inwardly-extended flanges 14 and 15 overlaps the inner ends of beams 10 at their upper parts, with the flange 14 disposed inside of and adjacent to flanges 11 of the end beams. Rivets 16 secure the parts together, and if it is desired to have the upper surface of bar 13 in the same plane with the upper surfaces of beams 10 the former may be depressed slightly at its ends, as at 17.

At the lower portion of the inner end of each beam 10 is attached, by means of rivets 18, a pair of spaced ears 19, to which are pivoted at 20 the two portions 21 and 22 of the bottom tension-rod, which are united at their inner ends by a turnbuckle 23 of the usual type having threaded engagement therewith. In the present instance the two plates 19 are attached to each beam 10, one on its outer surface and the other on its inner sur-

face; but our invention is not limited to this specific construction.

It will be observed from the structure described above that we have produced a metallic sill which is of light weight, but which, nevertheless, possesses considerable strength. It is also apparent that tension-rods 21 and 22, which together form in reality a single tension-rod, are connected by a turnbuckle 23, the rotation of which adjusts the length of the rod. Since the beam is made up of a number of small parts, if one or more become damaged they can be easily repaired or replaced, because they do not involve the handling or heating of any large parts.

Minor mechanical changes may be made in this structure without departing from the substance of our invention as defined in the following claims.

We claim—

1. In a device of the character described, the combination of two end beams, a center bar and a rod fastened to and connecting said end beams, substantially as described.

2. In a device of the character described, the combination of two end beams, a bar fastened to and connecting the upper portions of said beams, and a tension-rod connecting the lower portions of said beams, substantially as described.

3. In a device of the character described, the combination of two end beams deeper at their inner than at their outer ends, a bar fastened to and connecting the upper portions of the deep ends of said end beams, and a tension-rod fastened to and connecting the lower portions of the deep ends of said end beams, substantially as described.

4. In a device of the character described, the combination of two end channel-beams, a channel-bar fastened to and connecting the upper portions of said beams, and a tension-rod connecting the lower portions of said beams, substantially as described.

5. In a device of the character described, the combination of two end channel-beams deeper at their inner than at their outer ends, a channel-bar fastened to and connecting the upper portions of the deep ends of said end beams, and a tension-rod fastened to and connecting the lower portions of the deep ends of said end beams, substantially as described.

6. In a device of the character described, the combination of two end channel-beams deeper at their inner than at their outer ends, a channel-bar fastened to and connecting the upper portions of the deep ends of said end beams, a pair of ears secured to the lower portion of the deep end of each of said end beams, a tension-rod pivoted to each of said

pairs of ears, and a turnbuckle having threaded engagement with the free ends of said rods, substantially as described.

THOMAS DUNBAR.
ETHAN I. DODDS.
